UNITED STATES PATENT OFFICE

102,784

DESIGN FOR A RADIO CABINET

Alfred G. Hoffman, Cincinnati, Ohio, assignor to
Midwest Radio Corporation, a corporation of
Ohio

Application August 12, 1936, Serial No. 64,361

Term of patent 3½ years

To all whom it may concern:

Be it known that I, Alfred G. Hoffman, a citizen of the United States, residing at 909 Broadway, Cincinnati, in the county of Hamilton and State of Ohio, have invented a new, original, and ornamental Design for Radio Cabinets, of which the following is a specification, reference being had to the accompanying drawing, constituting a part thereof.

The single figure of the drawing is a view in perspective of a radio cabinet embodying my new design; a view in perspective from the right would be the same.

I claim:

The ornamental design for a radio cabinet substantially as shown and described.

ALFRED G. HOFFMAN.
